(57) **CLAIM**

The ornamental design for a handle, as shown and described.

DESCRIPTION

FIG. 1 is a front isometric exploded view of a handle in accordance with the present disclosure; and

FIG. 2 is a front view thereof;

FIG. 3 is a back view thereof;

FIG. 4 is a left side view thereof;

FIG. 5 is a right side view thereof;

FIG. 6 is a top view thereof; and

FIG. 7 is a bottom view thereof.

FIG. 8 is a front isometric assembled view of a handle in accordance with the present disclosure; and

FIG. 9 is a front view thereof;

FIG. 10 is a back view thereof;

FIG. 11 is a left side view thereof;

FIG. 12 is a right side view thereof;

FIG. 13 is a top view thereof; and

FIG. 14 is a bottom view thereof.

FIG. 15 is a front isometric assembled view of a handle of indeterminate length in accordance with the present disclosure; and

FIG. 16 is a front view thereof;

FIG. 17 is a back view thereof;

FIG. 18 is a left side view thereof;

FIG. 19 is a right side view thereof;

FIG. 20 is a top view thereof; and,

FIG. 21 is a bottom view thereof.

The handle is shown with a symbolic break in its length in FIGS. 15-21. The appearance of any portion of the article between the break lines forms no part of the claimed design.
